UNITED STATES PATENT OFFICE.

GEORGE A. MASTERS, OF CHICAGO, ILLINOIS.

REINFORCED CONCRETE CONSTRUCTION.

No. 916,748.

Specification of Letters Patent. Patented March 30, 1909.

Application filed September 23, 1907. Serial No. 394,049.

To all whom it may concern:

• Be it known that I, GEORGE A. MASTERS, a citizen of the United States, residing at Chicago, in the county of Cook and State of Illinois, have invented certain new and useful Improvements in Reinforced Concrete Construction, of which the following is a specification.

One of the objects of this invention is the production of a concrete wall or other structure in which materials of different qualities may be used in different parts of the structure, permitting the employment of high-grade material where needed and lower-grade material in the remaining parts of the structure.

Another object of the invention is the production of a concrete wall or other structure requiring no boxing or forms in its construction.

A further object is to provide an improved process for producing concrete structures.

The invention also relates to the other improvements in reinforced-concrete construction hereinafter set forth.

In the accompanying drawings, Figures 1, 2 and 3 are fragmental horizontal sections through a wall embodying the features of my invention, illustrating the same in different stages of construction. Fig. 4 is a fragmental vertical transverse section, and Fig. 5, a fragmental side elevation of said wall. Figs. 6, 7 and 8 are sectional detail views.

In carrying out my invention, I construct and set upon a suitable foundation *a*, a metallic framework comprising, in this instance, upright T-bars 1. In the case of a wall, the T-bars 1 are arranged in two rows with the stems of the T's extending inwardly, opposite T-bars of the two rows being secured together in pairs by means of cross-bars 2 bolted or otherwise secured to the stems of said T-bars. The T-bars of each row are secured together by means of horizontal wires 3 drawn through openings 4 formed in the flanges 5 of said bars. This method of securing the T-bars together permits of adjusting the position of said T-bars as desired by slipping them along said wires. The cross-bars 2 and horizontal wires 3 are placed at such distances apart as may be necessary to make a comparatively rigid framework for the proposed structure. The inner and outer sides of this framework are then covered with a suitable form of lathing for supporting the outer layers of material,

said lathing being put in place in the manner to be now described.

Upon both sides of the framework, at the bottom thereof, is placed a strip 6 of wire netting, expanded metal or the like, said strip extending for any suitable distance along the wall, preferably the entire length thereof, and being tied to the upright T-bars 1 by means of wires 7, Figs. 2 and 5. These strips of lathing material may be made of any suitable height, say, five feet. Along the top edge of the lathing material is placed a division member which may consist of a series of abutting horizontally-extending T-bars or angle-irons 8 tied to the uprights 1 by means of wires 9, the horizontally-extending flange of said division member preferably being equal in width to the distance between the proposed face of the wall and the T-bars 1. The outer sides of the strips 6 are then plastered with the desired facing material, such as water-proof cement mortar, said facing material being rubbed well into place, so that some of it shall pass through the lathing material, and securely anchor the facing material thereto. As soon as the facing material begins to set, its outer surface is trued up and given the desired finish. When the two thin walls thus formed have set, they constitute a mold into which the filling material for the wall, such as common concrete, is dumped. A section of the wall having thus been completed, another strip 6 of lathing material is secured to each side of the framework just above the division member 8, and a similar division member secured in place at the upper edge of said strip of lathing material. Said strips are then plastered and the interior filled with concrete or other filling material, as before described. This process is continued until the structure reaches the desired height.

A wall formed of the materials mentioned, and in the manner described, may be completed without the use of boxing or molds, the outer layers of the wall being made to serve the purpose of such molds. As will be seen, the portions of the wall exposed to weathering and other forms of wear may be made of high-quality materials, and the interior of the wall of cheaper, low-grade material. The division members 8 form gages for the thickness of the outside plaster coat, and guides for the straight-edge or other device used in truing up and smooth-

ing the face of said coat. Said division members also serve to divide the surfaces of the wall into panels, and thus enhance its appearance. They also form a division line 5 between the courses of the outside plaster shells, the edges of which courses could not be made to join satisfactorily, if said division members were omitted. Furthermore said members provide expansion joints for the 10 wall, thereby breaking up the surfaces of the wall into relatively small sections, it being well known that large cement surfaces are liable to cracking.

It is evident that various changes may be 15 made in the embodiment herein shown without departing from the spirit and scope of

my invention, therefore no undue limitation should be understood from the foregoing detailed description.

I claim as my invention:

A frame-work for reinforced concrete walls, comprising parallel rows of T-bars located opposite to each other in pairs; cross bars connecting opposite T-bars and horizontal members connected to said T-bars and 25 passing through the flanges of said T-bars on the opposite sides of their webs.

GEORGE A. MASTERS.
